UNITED STATES PATENT OFFICE.

JOHN ARTHUR HIRST, OF CHESTER, ENGLAND.

SWITCH GEAR FOR STARTING AND CONTROLLING ELECTRIC MOTORS.

Application filed July 18, 1924, Serial No. 726,846, and in Great Britain July 24, 1923. Renewed June 21, 1928.

This invention relates to switchgear, specially applicable for starting and controlling electric motors, but also applicable for use as circuit breakers having a quick make and break action; and the object is to provide efficient, compact and inexpensive switchgear particularly suitable for alternating current motor starters of the oil immersed star-delta type.

According to the invention, the gear comprises two switches having fixed contacts and moving contacts adapted to connect the respective fixed contacts, the respective moving contacts of the two switches being capable of independent spring-controlled movement and being adapted to be moved together in opposition to their respective springs by a common handle gear mechanism from their initial position to a position in which one or both of them connect respective sets of fixed contacts, and in which position one of them is retained by a detent, with or without no-volt or overload control devices, the other when the handle is released being returned by its spring to its initial position in which it makes connections with its fixed contacts which complete the "full-on" connections of the gear.

Preferably the moving contacts are arranged in drum form and will be referred to herein as drums, though any equivalent of the drum construction may be adopted; the moving contacts on the drum which, when the handle is released, is returned to its initial position, are employed in a motor starter as a connection changing switch, the moving contacts on the other drum being employed to make and break the circuit connections and will be referred to as the circuit breaker part.

Both drums are preferably adapted to be retained in the position into which they are moved by the handle gear by respective detents, the detent of the one (say the connection changing switch) being released by the movement of the handle to its initial position or by the return movement of an independent part from a position into which it is moved by the handle gear, the said movement being, if required, delayed by a time limit device; the detent of the other

part (the circuit breaker) being adapted to be released by a no-volt, or an overload device, or by a press button.

When used as a star delta motor starter, 55 the connection changing switch makes the delta connections in its initial position, but as the circuit breaker does not in this position connect the circuit, the said connections are not operative. When the two parts are 60 moved into the position in which they are retained by their detents, the connection changing switch makes the star connection and the circuit breaker connects to the supply mains. 65

On releasing the handle the connection changing drum returns to its initial position and makes the delta connections, thus completing the running connections of the motor, the said movement of the connection 70 changing switch being retarded if necessary by the employment of an independent releasing part controlled by a time limit device.

When the gear is used as a motor starter, 75 I preferably fit auxiliary fuses in addition to the main fuses in the circuit, the latter being connected so as to be permanently in the circuit and the former being connected in parallel with the latter when the switchgear is in the starting position. 80

The handle by which the gear is operated may be connected to the armature of a magnet energized by the main current, which armature prevents the return of the handle 85 to its initial position until the main current has fallen below a predetermined value.

The gear is also adapted to be operated by a press button, in which case a lever on the actuating shaft is connected to the armature of a magnet having opposing series and shunt windings, the arrangement being such that on closing the shunt windings by means of the press button switch the drums are moved into the position in which they are 95 retained by their detents, the return movement of the shaft which effects the release of the detent of the connection changing drum being delayed until the current in the series winding falls to a predetermined 100 value.

When the gear is used as a circuit breaker,

there are two gaps in each of the circuits to be controlled, the drum used as the connection changing switch in a motor starter closes one of the said gaps when in its initial position; when the two drums are moved to the positions in which they are retained by their detents, the last mentioned connection is broken, and the drum referred to as the circuit breaker drum bridges the other gap. When the first mentioned drum is released by the return movement of the handle, it returns to its initial position, and thereupon closes the other gap, so connecting the circuit to be controlled to the mains.

I have illustrated my invention in the accompanying drawings, in which:—

Figs. 1^A to 1^K show, diagrammatically, a simple form of the invention;—in these views Fig. 1^A is a sectional elevation of the drums, handle and shaft, Fig. 1^B an outside elevation, Fig. 1^C an end elevation of the handle and actuating piece, Fig. 1^D an end elevation of the drum A and its detent, and Figs. 1^E to 1^K views showing the several parts in the positions occupied during the operation of the gear.

Figs. 2^A to 4^C are similar views of a modification. In these views Fig. 2^A is an elevation, Fig. 2^B a fragmentary end view, and Figs. 2^C to 4^C views showing the several parts in the positions occupied during the operation of the gear.

Figs. 1 to 8^B are views similar to Figs. 1^A to 4^C but show an arrangement in which both the switch elements are controlled by separate and interlocked detents. In these views Fig. 1 is a side elevation, Fig. 2 a fragmentary end elevation, Fig. 3 a side elevation in section, Fig. 4 an inverted plan.

Figs. 5, 5^A and 5^B show the three parts of the switch in the "off" position. Figs. 6, 6^A and 6^B, Figs. 7, 7^A and 7^B show these parts in the intermediate positions, and Figs. 8, 8^A and 8^B show the parts in the "full-on" position.

Figs. 9, 10 and 11 are diagrammatic views showing the connections when the switch is arranged as a star-delta motor starter. Figs. 12, 13 and 14 are similar views to Figs. 9, 10 and 11, but show an arrangement of auxiliary fuses which are introduced into the circuit in the star position.

Figs. 15, 16 and 17 are similar views of the connections when the switch is arranged as a circuit breaker.

Figs. 18 to 24^B illustrate the preferred construction of the invention as applied to a star-delta motor starter.

In these figures Fig. 18 is an elevation with the casing shown in longitudinal section. Fig. 19 is a plan with the cover removed. Fig. 20 a plan with the switch elements in longitudinal section. Fig. 21 is a fragmentary end elevation. Figs. 22 to 22^D show the several parts of the switch in

the positions they occupy when the gear is in the "off" position.

Figs. 23 to 23^D and Figs. 24 to 24^B show the parts in intermediate positions, and Figs. 25 to 25^D show the respective parts in the "full-on" position.

Fig. 26 is an elevation showing an overload and no-volt control device adapted to operate the circuit breaker detent.

Fig. 27 is a similar view showing the detent operated.

Fig. 28 shows a time element overload control of the circuit breaker detent.

Fig. 29 is a side elevation, and Fig. 30 an end elevation of an electro-magnetic control device for the operating handle.

Fig. 31 is an elevation, and Fig. 32 a part plan of electro-magnetic means for operating the switch by a distance control, and

Figs. 33 to 38^B illustrate the arrangement in which the release of the detent which holds the connection-changing switch against its spring in the position into which it has been moved by the operation of the handle, is effected independently of the return movement of the handle by means controlled by a time limit device;

Fig. 34 being an elevation;

Fig. 35 a side elevation;

Fig. 35 a fragmentary elevation partly in section; and

Figs. 36 to 38^B elevations of the several parts in the successive positions they occupy in the operation of the gear.

Referring first to Figs. 1^A to 1^K,—the moving parts of the two switch elements are carried on two respective drums A and C, rotatably mounted on a fixed shaft 2 carried in a casing or bracket 1. Springs a^5 and c^5 are fitted to the drums, they may be housed in the drums and be connected respectively between the drums and the fixed shaft, the drums being made in halves or having detachable ends to admit the springs; the springs tend to turn the drums in the direction of the arrow Figs. 1^C and 1^D, and to maintain them in their initial position, in which the lugs 12 on the drums engage with the fixed stops 11.

A handle 3 connected to an actuating piece B is loosely mounted on the shaft, and may be fitted with a spring 3' tending to move it in the direction of the arrow Fig. 1^C, the movement of the handle may be limited by fixed stops 5 and 6.

The actuating piece B has a slot b^1 which is adapted to engage with a pin c^2 fixed to the drum C. The drum C has a pin c adapted to engage with a slot a in the end of the drum A.

The drum A has a detent a^3 adapted to engage with a tooth a^3 in the drum.

If the handle be turned in the direction of the arrow, through say 90°, it will be seen that it will turn the two drums simultaneous-

ly through 90° and that the drum A will be held in this position, but that the drum C will, when the handle is released be turned back by its spring to its initial position.

Before describing the electrical connections, it may be convenient to describe a modification in the mode of mounting and actuating the drums, shown in Figs. 2^A to 4^C.

In this modification the shaft 2 is rotatable in the casing 1 and the handle 3 and actuating piece B are fixed to the shaft. The actuating piece is located between the drums A and C and has two slots b¹ and b² adapted respectively to engage with the pins c² fixed to the drum C and the pin a² fixed to a ratchet a¹ pinned by a pin 7 to the drum A.

The springs a⁵ and c⁵ are now fitted at the ends of the drums, and the movement of the handle is limited by the engagement of a tail piece 4 with stops 5 and 6, the drum springs tend to turn the drums in the direction of the dotted arrow Fig. 2^C so that in their initial position the lugs 12 engage the fixed stops 11.

The action is substantially the same in the two modifications. In each case three phase current connections are shown.

In each modification the drum A carries oppositely disposed connected contacts a⁴, d⁴, adapted to connect the fixed contacts a⁶, a^{6'}; and the drum C carries similar contacts c⁴, c^{4'} adapted in different angular positions to connect the respective pairs of the fixed contacts C⁶, C^{6'} and c⁷, c^{7'}.

In the initial position of the drum A the contacts a⁴ on the drum A are clear of the fixed contacts a⁶, and a^{6'} but in the position into which the drum is moved by the handle and in which it is retained by the detent a³, the two sets of fixed contacts a⁶ and a^{6'} are connected together by the two opposite sets of contacts a⁴ which are respectively connected together by the conductors shown in chain-dotted lines.

In the initial position of the drum C the opposite sets of moving contacts c⁴ which are respectively connected by conductors shown in chain-dotted lines may connect together the opposite sets of fixed contacts c⁷, c^{7'}. In the position of the drum C shown in Fig. 1^E and Fig. 3^C the opposite pairs of contacts c⁶, c^{6'} are connected together, and in the final or "full-on" position of the gear the pairs of fixed contacts c⁷, c^{7'} are connected together.

The drum A may therefore be used as a circuit-breaker to connect the main circuit through the pairs of fixed contacts a⁶, a^{6'} to any required circuit, whereas the switch C may be used as the connection-changing switch; as will be seen from inspection of Figs. 1^E, 1^F, 2^A and 2^C, the connection together of the fixed contacts c⁷, c^{7'} in the initial position of the drum C is ineffective

since the contacts a⁴ on the drum A in this position of the gear are not connected to contacts a⁶, a^{6'}. In the position shown in Figs. 1^G and 1^H, and Figs. 3^A, 3^B and 3^C the fixed contacts a⁶, a^{6'} are connected through the drum A and the fixed contacts c⁶, c^{6'} are connected through the drum C. Finally, as shown in Figs. 1^J, and 1^K and Figs. 4^A and 4^C, when the handle is released the drum A is held so as to maintain the connection between the fixed contacts a⁶, a^{6'}, the drum C returning to its initial position connecting the fixed contacts c⁷, c^{7'}.

The switch may therefore be used for any purpose in which the drum A is employed to make and break the main circuit or the like connections, and in which the switch C is used to change the connections, and it will be seen as hereinafter described that the arrangement is particularly suitable for a star-delta motor starter, in which case the fixed contacts c⁷, c^{7'} may be dispensed with, and the contacts c⁴ carried on the drum C, (see Figs. 9 to 11) which in one position of the drum connect the two sets of fixed contacts c⁶, c^{6'}, whilst in the other position of the drum a bar contact c¹⁰ carried by the drum C short-circuits the one set of three contacts c⁶.

The detent a³ may in each modification be fitted with a tail-piece 13 controlled by a spring 14 and adapted to be released by an overload device 15 comprising a solenoid connected in the main circuit, the core of which, upon an excess current, rises and strikes the arm 13 and so releases the detent.

The detent a³ is also adapted to be released by hand, in order to open the switch gear, by means of the push-button 16.

Figs. 1^E to 1^K, and Figs. 2^C to 4^C show the different parts in the positions they occupy, before the handle is operated, after it has been operated, and after it has been released.

In the arrangements described the drum C is forced by its spring c⁵ to its initial position upon the release of the handle, but in order to ensure that this movement shall give a quick make and break we prefer to fit to the drum C a ratchet such as a¹ and a second detent such as a³, and to interlock the second detent.

This arrangement is illustrated diagrammatically in Figs. 1 to 8^B:—The drums A and C are, as before, freely mounted on a shaft 2 rotatably mounted in the casing 1 and operated by the handle 3, the tail piece 4 moving between stops 5 and 6; as in the arrangement described each drum is provided with springs a⁵ and c⁵ respectively tending to rotate the drums in a clockwise direction, and with stop pieces 12 which in the initial positions are maintained by the springs against fixed pins 11.

As before the actuating piece B is fixed to the shaft 2 say by having a square bore 130

mounted on a square collar on the shaft. The drum A is provided with a ratchet a^1 fixed to the drum by the pins 7 and the drum C is provided with a ratchet c^1 similarly fixed to the drum C by pins 7. The respective ratchets carry pins a^2 and c^2 fixed thereto, and the actuating piece B is mounted between the two ratchets so that the pin c^2 engages with the slot b^1 and the pin a^2 with the slot b^2 in the actuating piece B. In the initial position the location of these pins in the respective slots is as shown in Figs. 5 to 5^B, from which it will be seen that if the shaft and with it the actuating piece B are turned in a counter-clockwise direction the gear will be moved into the position shown in Figs. 6 to 6^B. The drums A and C are held in this position by means of detents a^3 and c^3 fulcrumed on a pin 8 carried in a bracket 9, the detent a^3 engaging with a tooth a^8 on the ratchet a^1 , and the detent c^3 engaging with a tooth c^8 on the ratchet c^1 .

The engaging piece B is provided with a locking and releasing tooth b^3 and the detent c^3 is provided with a locking piece c^9 ; the detent a^3 is provided with a fixed pin a^7 which lies inside the detent c^3 and which when the detent a^3 is in the disengaging position (see Fig. 5) is adapted to hold the detent c^3 in such position that its locking piece c^9 is thrown clear of the locking and releasing tooth b^3 . The detent a^3 is provided with a tail piece 13, spring 14 and overload device 15 as previously described. In the initial position of the gear, before the handle is operated the position of the respective parts is shown in Figs. 5, 5^A and 5^B. If now the handle 3 be operated, in opposition to a spring 16, in a counter-clockwise direction, the respective engagement between the ends of the slots b^1 and b^2 with the pins c^2 and a^2 turn the parts into the position shown in Figs. 6, 6^A and 6^B in which the ratchet a^1 and the drum A are held against the spring a^5 by the detent a^3 and in which the ratchet c^1 and drum C are held against the spring c^5 by the detent c^3 . In this position the desired connections between the two sets of fixed contacts a^6 and the two sets of fixed contacts c^6 are made. If now the handle be released it and the disc B will be urged by the spring 16 into the position shown in Fig. 7^A in which it will be seen that the locking and releasing tooth b^3 is engaging with the locking piece c^9 and this moves the detent c^3 radially outwardly causing it to release the tooth c^8 , whereupon the spring c^9 returns the drum C and ratchet c^1 to the position shown in Figs. 7^B and 8^B. The ratchet c^1 has a clearance space c^{10} which as soon as the locking and engaging tooth b^3 has passed the engaging piece c^9 permits the detent c^3 to fall back so that b^3 is locked by c^9 as shown in Fig. 8^A. The object of this lock is to prevent the movement of the han-

dle in a clockwise direction whereby the drum C could be turned into the position shown in Fig. 6^B.

In the meanwhile the ratchet a^1 and drum A have been held in the "on" position as shown in Figs. 6 to 8 by the detent a^3 , thus maintaining the connections between the two sets of fixed contacts a^6 whilst the contact made in the position of the drum C shown in Fig. 8^B is that which gives the desired change of connections in say a motor starter.

In order to release the gear and bring the drums back to the initial position the detent a^3 is tripped by means of a push-button 16 engaging with the tail-piece 17 on the detent a^3 .

Figs. 9 to 11 show the connections necessary to enable a switch constructed as described to be employed as a star-delta motor starter. The several parts in Figs. 9 to 11 are lettered to correspond with the diagrammatic views in Figs. 1 to 8^B.

The respective opposite sets of contacts a^4 on the drum A are connected together by the conductors 18 shown in chain-dotted lines, and the two sets of contacts c^4 on the drum C are respectively connected by the conductors 19. A bar contact c^{10} is fitted to the drum C at right angles to the contacts c^4 , the upper set of fixed contacts a^6 are respectively connected to the supply mains D, and the corresponding lower set of fixed contacts $a^{6'}$ are respectively connected by the conductors 20 to the fixed contacts $c^{6'}$ and the latter are connected respectively by the conductors 21 to one set of ends of the stator windings I, II, III, the opposite ends of which latter are connected to the fixed contacts c^6 .

In the initial position shown in Fig. 9, the set of contacts c^6 are connected to the set of contacts $c^{6'}$, but since in this position the contacts a^6 are disconnected from the contacts $a^{6'}$, the motor is not connected to the supply mains D. In Fig. 10 the two drums are moved into the position shown in Fig. 6 and 6^B in the diagrammatic views described, and it will be seen that the mains D are connected to one set of ends of the stator winding, and the other ends of the latter are short circuited by the contacts c^{10} . This gives the star position; on releasing the handle the drum C moves to the position shown in Fig. 11 and this gives the delta or running connection for the motor.

It is desirable that the heavier currents should be permitted in the star connection than in the delta connection; and where an electro-magnetic overload release is provided it may be fitted with an arrangement actuated by the movement of the drum C or by the movement of the handle whereby its sensitiveness is reduced in the star position, and restored when the delta position is reached. Preferably however the same re-

sult is accomplished by fitting, in addition to the usual or main fuses in the main circuit, auxiliary fuses which in the star position are in the star position of the gear, by 5 the movement of the drum C or by the movement of the handle, connected in parallel with the main fuses. This arrangement is shown diagrammatically in Figs. 12 to 14 in which the parts are lettered to correspond 10 with the diagrammatic views already described.

In addition to the main fuses F fitted in each of the mains, auxiliary fuses F' are also fitted, ends of each of the auxiliary 15 fuses being permanently connected to one end of the corresponding main fuse, the other ends of the auxiliary fuses being adapted to be connected to the corresponding other ends of the main fuses through 20 switch gear actuated by the operation of the main switch gear.

According to one alternative (see Figs. 12 to 14) the ends of the auxiliary fuses F' are connected by conductors 22 to three fixed 25 contacts f¹, and three corresponding contacts f are connected by the conductors 23 to the main circuit. On the drum C are mounted two oppositely located sets of three contacts f² which are respectively connected together 30 by the conductors 24 shown in chain-dotted lines. When the switchgear is moved in the manner described to the star position shown in Fig. 13, and in this position only, the auxiliary fuses F' are introduced into 35 the circuit in parallel with the main fuses F.

The switch may conveniently be employed as a circuit breaker in which case the connections are as shown in Figs. 15 to 17. The contacts a⁶ are connected to the supply 40 mains D, the contacts a⁶' are connected to contacts c⁶ by the conductors 20, and the contacts c⁶ are connected to the circuit terminals V. In the initial position, shown in Fig. 15, the contacts c⁶ and c⁶' are connected 45 by the contacts c⁴ as described, but the contacts a⁶ and a⁶' are not connected. The first movement of the handle moves the two drums, in the manner described, into the 50 position shown in Fig. 16 where a⁶ and a⁶' are connected by the contacts a⁴, but the contacts c⁶ and c⁶' are now disconnected.

On releasing the handle the drum C moves in the manner described into the position shown in Fig. 17 in which the supply mains 55 D are connected to the circuit terminals V through the two sets of contacts. It will be seen that when the switch is arranged as a circuit breaker the final connections made by the drum C in Fig. 17 are made by a 60 quick-make action since the drum C is, in the manner described, propelled by its spring with a quick action into the position shown in Fig. 17; the arrangement when used as circuit breaker also possesses the ad-

vantage of a loose handle circuit breaker 65 since should an overload occur on making the connections by the drum C shown in Fig. 17, the detent a³ (see Fig. 5) would be disengaged by the overload device 15 and so 70 break the circuit of the drum A, notwithstanding that the handle was held fixed. It will further be seen that when the circuit is broken by the action of the overload device, or by the press button in the ordinary way, the detent a³ is released and the drum A flies 75 back to its initial position, thus breaking each circuit with a quick break action.

Referring now to Figs. 18 to 25^D which 80 show the constructional embodiment of the invention when applied to an oil immersed star-delta motor starter; G is the main casing by which the gear is enclosed and H the oil container detachably bolted thereto, g¹ is the enclosing cover.

The shaft 2 upon which the drums and ratchets are mounted is in this arrangement immersed in the oil, and in order to take the handle shaft through the casing at a point above the oil level the handle shaft 2^a is made separate from the shaft 2, and is 90 carried through the boss 25 and connected to the shaft 2 by means of the two levers 26 and 27 and the connecting rod 28. Movement into the shaft 2^a is limited by fixing 95 stops 5 and 6 see Fig. 21 with which a tail piece 4 on the handle engages; and a spring 16 is interposed between the lever 26 and the pin 16' carried by the casing, the said spring normally tending to move the handle to its 100 "off" position. The equivalents of the drums A and C in the diagrammatic views previously described are constructed as follows:—

Centre pieces 30 of cylindrical bore, fitting 105 the shafts, are of square external configuration, and the squared portions are covered with insulation 31, the exterior of which is of square configuration; the carriers 32 on which the contacts c⁴, c¹⁰ and a⁴ are carried have a square bore which is a tight fit on the insulation, and discs of insulation 33 are fitted on each side of the contacts so as to prevent arcing between them. Contacts c⁶ and a⁶ (see Fig. 22^C) are pivotally carried 110 from brackets 34, and are caused to give the necessary contact pressure by plate springs 34^a; the brackets 34 are carried from a frame plate 35, from which also are carried, by brackets 36, the end bearings 37 in which the shaft 2 is mounted. The ends of the 115 centre pieces 30 are screw-threaded and at the outer end of each centre piece is secured a spring box 38, in which a spiral spring 39 is housed, one end of each spring being attached to the fixed bearing 37 and the other end being attached to the interior of the spring box, the end of the spring box being of square bore which fits a square part 120 125

of the centre piece 30; the spring boxes are fixed in position by a nut 40; the end of the spring box is closed by an end plate 41.

The contacts a^4 , c^4 and c^{10} are renewable, as 5 also are the contacts a^6 and c^6 , and the latter are connected to the usual circuit terminals. All contacts at which the circuit is broken by the action of the switchgear are immersed in oil contained in the container H.

10 At the inner end of the centre piece which constitutes the element A of the switch, a ratchet a^1 is fixed after the manner described in connection with the spring box, by means of a nut 42, and at the adjacent end of the 15 centre piece constituting the switch element C a ratchet c^1 is fixed by means of a nut 43, and between these two ratchets the actuating piece B is carried, the latter being keyed or otherwise secured to the shaft so as to rotate therewith. The constructions of the 20 ratchets a^1 and c^1 and of the actuating piece B, the slots b^1 and b^2 in the latter and the respective pins a^2 and c^2 in the ratchets and engaging the slots, are as described in the 25 modifications referred to, and as illustrated in detail in Figs. 22, 22^A and 22^B.

The ratchet a^1 is fitted with a detent a^3 and the ratchet c^1 is fitted with a detent c^3 . These detents are carried (see Figs. 18 and 30 22^E) by being fitted on a pin 8 carried from a fixed bracket 9, and they are provided with a spring 44 which tends to press the detents into contact with their respective ratchets. The detent a^3 is fitted with an arm 45 (see 35 Fig. 22) on which, when the gear is disconnected from the mains, rests the armature j^1 of a no-volt release device J. When the coil J is unexcited the weight of the armature j^1 holds the detent a^3 clear of the ratchet 40 a^1 , when however J is excited the armature j^1 is raised and the spring 44 (see Figs. 18 and 22^E) presses the detent a^3 into contact with this ratchet. The detent a^3 is also adapted to be released by means of the press 45 button 46 making contact with the tail 47 of the detent a^3 . The detent a^3 carries a pin a^7 which extends under the detent c^3 . The action of the apparatus will be understood from Figs. 22 to 25^D. Figs. 22 to 22^D show 50 the two ratchets a^1 and c^1 , the actuating piece B and the drums A and C in the initial position, and it will be seen that as the detent a^3 is moved outwardly by contact with the periphery of the ratchet a^1 , the pins 55 a^7 attached to a^3 move the detent c^3 out to a corresponding degree, and in this position the locking piece c^9 of the detent c^3 is clear of the locking and releasing tooth b^3 on the actuating piece B. It will be seen in this 60 position that the contacts c^4 connect the contacts c^6 and $c^{6'}$ but that the contacts a^4 are clear of the contacts a^6 and $a^{6'}$. This gives the connections shown in the diagram Fig. 9. Figs. 23, 23^D show the position of the

several parts when the handle is moved 65 counterclockwise through say 90°; the slots b^1 and b^2 in the actuating piece B have carried the pins a^2 and c^2 into the position shown in Fig. 23^A; this has caused the movement of the ratchets a^1 and c^1 and the drums 70 A and C into the position shown in Figs. 23, 23^B, 23^C and 23^D; the detent a^3 holds the drum A and the detent c^3 holds the drum C in this position; in this position it will be seen that the contacts a^4 now connect the contacts a^6 and $a^{6'}$ and that the contacts c^{10} short-circuit the three contacts a^6 . This gives the connections shown in Fig. 10. If now the handle be released, the locking and releasing tooth b^3 will engage the locking 80 piece c^9 and will push the detent c^3 clear of the tooth c^8 whereupon the ratchet c^1 will take the position shown in Fig. 24^B, and the drum C would take the position shown in Fig. 25^D. A slight further movement of the 85 handle moves the releasing and locking tooth b^3 past the locking piece c^9 whereupon the detent c^3 takes up the position shown in Figs. 24^A and 25^B, the clearance c^{10} in the ratchet c^1 permitting this movement of the 90 detent.

The locking piece c^9 now engages the locking and releasing tooth b^3 . This locking of the actuating piece B prevents movement of the actuating handle in a counter-clockwise 95 direction and the projection 4 bearing against the stop 6 (see Fig. 21) prevents movement of the handle in a clockwise direction, the gear is therefore locked in the position into which it has now been moved, 100 and can be released only by the actuation of the no-volt release device, or by the actuation of the press-button 46.

It will be noticed that throughout the movements last described the ratchet a^1 has 105 been held in the position shown in Figs. 23, 24 and 25, and the drum A in the position shown in Figs. 23^C and 25^C, in which the contacts a^4 are connected to contacts a^6 and $a^{6'}$ and that in the final movement of the drum C the contacts c^4 connect the contacts c^6 and $c^{6'}$, this gives the connections shown in Fig. 11 and is the position of the gear for the running position of the motor.

In the arrangement described in Figs. 18 to 25^D, the detent a^3 is shown as being operated by a no-volt release device, it may, however, be arranged to be operated by a no-volt release device and an overload release device. This is shown in Figs. 26 and 27, where J^2 is a no-volt release device, the armature j^2 of which, when the magnet coil is deenergized, falls on the arm 48 (see Fig. 27) of the detent a^3 and so releases the ratchet a^1 . Should an overload occur the core m^1 of an overload magnet M capable of adjustment in known manner, is raised and strikes the releasing pin m^2 which, by en-

gagement with the arm 49 (see Fig. 27) of the detent c^3 , causes the release of the latter upon an overload.

The overload release device may be fitted with a dash-pot so as to give it a time-lag, and such an arrangement is shown in Fig. 28. In this case a piston m^3 is connected to the armature m^1 of the overload device M, said piston being caused to move in a cylinder filled with oil, when the core m^1 is actuated and rises the flow of oil from one side of the piston to the other is restricted, but said flow is comparatively free when the piston falls; thus the upward movement of the core m^1 is checked and the degree of checking may be adjusted; the construction and arrangement of a dash-pot for this purpose is, of course, well known.

In some cases in motor starter arrangements, when the handle 3 has been moved to the position in which the star connection of the switch has been made, the return movement of the handle may be subjected to magnetic restraint, the degree of which is controlled by the main motor circuit; in this way the handle may be held against the return movement which releases the detent c^3 as described, until the said current is reduced to normal value after the motor has accelerated. Such arrangement is shown in Figs. 29 and 30.

In this arrangement the rod 28 which connects the lever 26 to the lever 27 mounted on the main shaft 2 (as in Fig. 21) is extended at 28' and is connected to an armature o^1 of the electro-magnet O, the winding of which is connected in the main circuit. When the handle 3 has been operated so as to turn the gear into the star position, the armature o^2 is attracted to the core o^3 by a force which, until the main current is reduced to its normal value, prevents the return movement of the handle 3. In other respects the gear is similar to the modifications described.

In some cases instead of operating the gear by means of the handle 3, it may be electro-magnetically operated, and such an arrangement is illustrated in Figs. 31 and 32.

In this case a lever 27 mounted on the shaft 2 (as shown for example in Figs. 18 and 21) is connected by a rod to the armature o^4 of a solenoid o^2 . This solenoid comprises a shunt winding o^5 which is excited by a distant press-button, and the shaft is, when the shunt winding o^5 is energized, moved into the position corresponding with the star connections of the gear when used as a motor starter; and, when the said shunt circuit is broken the shaft moves back into the position corresponding with the delta connection. The magnet may be provided with two windings, a shunt winding o^5 the circuit of which is closed by a press-button, and the winding o^6 in series with the main

circuit, which two windings are opposed. On closing the circuit of o^6 , say by means of a press-button, the gear is moved into the star position, and it is held in this position by the excess ampere turns of the winding o^6 over the winding o^5 ; as the motor accelerates the current in o^6 falls and when its magnetizing effect is approximately equal to that of o^5 , the currents in the windings o^5 and o^6 being oppositely wound neutralize each other, whereupon the armature o^4 falls and the gear is turned into the delta position.

In the modifications described the detent c^3 , which by engagement with the ratchet c^1 , holds the drum C (usually arranged as a connection-changing switch) against its spring in the position to which this drum has been turned by the handle, is released by the return movement of the actuating piece B operated by the handle. The detent c^3 , may, however, be released by means which act independently of the return movement of the handle, and the time taken by such means to effect the release may be controlled by any convenient method such as a dash-pot, electro-magnetic brake, or a rotating vane.

In Figs. 33 to 38^B a modification of the gear arranged as a star-delta motor starter is illustrated, in which the detent c^3 is released by means controlled by a train of wheels and a rotating vane, so that the drum C which is the connecting-changing switch, is automatically released to make the delta connection upon the expiry of any desired time interval after the star connection has been made.

The arrangement of the drum A forming the circuit breaker and the drum C forming the connection changing switch, the spring boxes 38 and spiral springs 39, therein, the shaft 2 and the lever 27 thereon, the rod 28, the handle shaft 2^a, the lever 26 and the handle 3, may be arranged in accordance with the modification last described; the ratchet c^1 , its pin c^2 , the tooth c^8 and clearance space c^{10} are also constructed as described; and the detent c^3 is, as before, fitted with a locking piece c^9 .

In the arrangement of Figs. 33 to 36^B the locking piece c^9 instead of being released by a projecting tooth b^3 on the actuating part B, is adapted to be released by a tooth p^1 on a releasing piece P mounted on the shaft 2, controlled by a spring p^3 and having a pin p^2 entering a third slot b^8 in the actuating piece B (see Figs. 36 to 36^B). The releasing piece P has a clearance slot p^4 through which the pin c^2 fixed to the ratchet c^1 , (see Fig. 35) passes, to permit of the engagement of the said pin c^2 in the slot b^1 in the actuating piece B, the releasing piece P has also a quadrantal toothed portion p^5 which engages with a pinion p^6 mounted on a lateral

shaft p^7 , said pinion p^6 being loosely mounted on the shaft p^7 and being connected to one member p^8 of a ratchet free wheel device, the other member p^9 of which is keyed to the shaft p^7 ; engagement between the teeth of p^8 and p^9 is effected by the spring p^{17} . Keyed to the shaft p^7 is a wheel p^{10} engaging with a pinion p^{11} in a shaft p^{12} , on which latter is mounted a spur-wheel p^{13} 10 engaging with a pinion p^{14} on a shaft p^{15} on which the rotating vane p^{16} is mounted.

The releasing piece P is, by the engagement of the pin p^2 with the slot b^8 in the actuating piece B, turned in the direction of 15 the arrow (Fig. 37) by the handle 3 and actuating piece B, and in opposition to the spring p^3 , into the position shown in Fig. 37^A, this movement being unrestrained by the ratchets p^8 , p^9 , owing to the yielding of 20 the spring p^{17} on the shaft p^7 permitting the "free-wheel" movement of the pinion p^6 .

When the handle is released, and moved back to its initial position by its spring 16, the releasing piece P is urged by its spring 25 p^3 in the direction of the arrow (Fig. 37^A), such movement, however, is controlled by a train of wheels and the rotating vane p^{16} , so that the necessary time interval elapses before the releasing piece P is moved into the 30 position shown in Fig. 37^B in which the tooth p^1 engages the locking piece c^9 imparting angular movement to the detent c^3 , whereby it releases the ratchet c^1 , allowing it to move into the position shown in Fig. 35 38^B, in which position the connection-changing switch C makes the delta connection. The head of the detent c^3 moves into the clearance space c^{10} (see Fig. 38^B) whereupon the releasing piece P is locked by the engagement of the tooth p^1 with the locking piece c^9 (see Fig. 37^C).

The detent c^3 is moved to release the locking piece when the detent a^3 is actuated as described either by the press-button or by 45 the no-volt or overload release device as the case may be, a suitable connection, such as the pin a^7 (Fig. 18) fixed to the detent a^3 operates the detent c^3 when a^3 is released.

In other respects the action of the apparatus is as described in connection with Figs. 50 18 to 25.

Having now fully described my invention I declare that what I claim and desire to secure by Letters Patent is:—

55 1. In electric switchgear in combination;—two movable switch parts; fixed contacts with which one of the switch parts contacts when in its initial position; fixed contacts with which the said switch part contacts when in its secondary position; fixed contacts with which the other switch part contacts when in its secondary position; means tending to move both switch parts into their initial positions; operating mechanism 60

nism adapted to move the two said switch parts in opposition to the said means from their initial positions to their secondary positions; a detent device adapted to hold the second mentioned switch part in its secondary position; and means adapted to release the said detent device; substantially as described: 65

2. In electric switchgear in combination;—two movable switch parts; fixed contacts with which one of the switch parts contacts when in its initial position; fixed contacts with which the said switch part contacts when in its secondary position; fixed contacts with which the other switch part contacts when in its secondary position; means tending to move both switch parts into their initial positions; operating mechanism 70 adapted to move the two said switch parts in opposition to the said means from their initial positions to their secondary positions; a detent device adapted to hold the second mentioned switch part in its secondary position; means adapted to release the second detent device; detent means adapted to hold the first mentioned switch in its secondary position; and means for releasing the said detent; substantially as described. 75

80 3. In apparatus as claimed in claim 2, means for releasing the detent of the first mentioned switch part, said means being actuated by the operating mechanism and being adapted to effect the said release when the operating mechanism is returned to its initial position; substantially as described. 90

4. In apparatus as claimed in claim 1, 100 mounting the respective moving switch parts on two drums rotatably about a common shaft, and fitting each with a spring tending to move it into its initial position; and providing the operating gear with engaging means which when angular movement is given to the operating gear in the one direction, engage with engaging parts on the said drums and move the drums from their initial 105 to their secondary position, the operating gear being free to return to its initial position; substantially as described. 110

5. In apparatus as claimed in claim 2, providing the detent of the second mentioned switch part with means which when the said detent is released, engage the detent of the first mentioned switch part and release it; substantially as described. 115

6. In combination with apparatus as claimed in claim 2; means actuated by the operating mechanism and adapted when the operating mechanism is returned to its initial position to effect the release of the detent of the first mentioned switch part; locking means fitted to the said detent and adapted 120 to hold it after it has been released by the release means actuated by the operating mechanism; and means on the detent de- 125

- vice of the first mentioned switch part adapted when the said detent device is released to release the locking means of the first detent part; substantially as described.
5. 7. In apparatus as claimed in claim 2, releasing means for the detent of the second mentioned switch part; said means being actuated upon failure of supply of electric current; substantially as described.
10. 8. In apparatus as claimed in claim 2, releasing means for the detent of the second mentioned switch part said means being actuated when the current controlled exceeds a predetermined limit; substantially as described.
15. 9. In apparatus as claimed in claim 2, releasing means for the detent of the second mentioned switch part said means being actuated upon the failure of supply of current, 20 and also being actuated when the current

controlled exceeds a predetermined limit; substantially as described.

10. In apparatus as claimed in claim 2, releasing means for the detent of the first mentioned switch part actuating to release the 25 said detent when the operating mechanism is returned to its initial position; substantially as described.

11. In apparatus as claimed in claim 2, releasing means for the detent of the first mentioned switch part actuated to release the rendered potential to release by movement of the actuating mechanism and being fitted with a time element device adapted to provide a time interval between the said actuation and release; substantially as described. 30 35

In witness whereof I have hereunto set my hand.

JOHN ARTHUR HIRST.
